UNITED STATES PATENT OFFICE.

LIBBIE BORDEN, OF SPOKANE, WASHINGTON.

REFRIGERATOR.

No. 824,061.

Specification of Letters Patent.

Patented June 19, 1906.

Application filed July 10, 1905. Serial No. 268,985.

To all whom it may concern:

Be it known that I, LIBBIE BORDEN, a citizen of the United States, residing at Spokane, in the county of Spokane and State of Washington, have invented a new and useful Refrigerator, of which the following is a specification.

This invention relates to refrigerators, and has for its object to improve the construction 10 and increase the efficiency and utility and produce a simply-constructed device of this character so arranged that all the interior parts may be readily removed for thorough cleaning or renewal.

Another object of this invention is to provide a simply-constructed device of this class wherein means are provided for filtering and saving the water from the melting ice.

With these and other objects in view the 20 present invention consists in the combination and arrangement of parts, as will be herein-after fully described, shown in the accompanying drawings, and particularly pointed out in the appended claims.

In the drawings, Figure 1 is a sectional front elevation of the improved device. Fig. 2 is a section on the line 2 2 of Fig. 1. Fig. 3 is a section on the line 3 3 of Fig. 1. Fig. 4 is a transverse section on the line 4 4 of Fig. 1. Fig. 5 is a front elevation, partly in section. Fig. 6 is a sectional detail illustrating a modification in the construction of the inclosing walls of the casing.

The casing or closure of the device is 35 formed with hollow walls, the outer member at 10, the inner member at 11, and the non-conducting filling at 12, the latter of any of the well-known materials—such as charcoal, asbestos, or the like—usually employed for 40 this purpose.

The inner wall 11 is formed of sheets of enameled metal, the enamel being of the quality usually employed upon culinary vessels of various kinds, while the outer wall may be 45 wood, as represented in Figs. 1, 2, 3, and 4, or with both walls of the enameled metal, as indicated in Fig. 6, as may be found most desirable.

Connected to the inner wall 11 of the casing at the upper portion are cleats 13, upon which a pan-like structure 14 rests, the structure for containing filtering material indicated at 15, of any suitable kind. Near its rear side the pan 14 is provided with a vertical division member or partition 16, of wire screen or like material. The partition 16 is

preferably located near the rear wall of the casing, and the discharge from the filter leads from the compartment formed by the partition 16, as hereinafter explained. 60

Secured upon the inner walls of the filter-pan 14, near its upper edge, are cleats 18 for supporting the tray 19 for containing the ice, the tray having apertures 20, through which the water resulting from the melting ice falls 65 into the filter and is conducted thence, after being purified, through the screen-partition 16 and thence to the discharge therefrom.

The filter-pan 14 is provided with hand-holds 21, and the ice-tray 19 is provided with 70 hand-handles 22 to facilitate handling the same when removing them from and inserting them into the casing. The filter-pan thus makes a transverse partition within the casing and divides the same into two compartments, the portion above the ice-tray 75 being the ice-chamber and the portion below being the provision-chamber, as herein-after more fully described.

The top portion 23 of the casing is hinged 80 at the front, as at 24, and opens toward the front and folds down over the same to provide for inserting the ice into the ice-chamber.

Attached to the under side of the filter-pan 14 are spaced guides 25 26, and similar spaced guides 27 28 are disposed upon the bottom member of the provision-chambers, and slidably engaging those spaced guides are partition-plates 29 30, the plates thus 90 dividing the provision-chamber into three compartments—two relatively large side compartments and a narrow central compartment, as indicated in Fig. 1—the partition-plates being removable when it is required to cleanse the refrigerator. 95

Attached to the outer faces of the plates 29 30 are spaced cleats 31 32, and attached to the inner faces of the end members 11 of the casing are similar cleats 33 34, the cleats 100 31 33 for detachably supporting shelves 35 and the cleats 32 34 for detachably supporting shelves 36.

The front portion of the casing opposite the ice-chamber is built in with the remainder of the casing, as shown, while the space opposite the larger provision-compartments are closed by doors 37 38, hinged, respectively, as at 39 40, to the end walls of the casing, while the portion of the front opposite the central narrow compartment formed by the plates 29 30 is closed by a 110

- member 41 of the same width as the central compartment. The doors 37 38 seat against this central closure member 41 by their inner swinging edges and are provided with latches 5 42 43, engaging keepers 44 45 on the member 41, while the latter is in turn detachably supported in position by bolts or other suitable detachable fastening, as at 46 47. The doors 37 38 and central closure member 41, together with the ice-chamber 23, are formed with outer and inner walls spaced apart and preferably filled with non-conducting material in the same manner as the remaining portions of the casings, as shown.
- 15 Detachably disposed in the narrow central compartment between the plates 29 30 is a water-receiver 48, having an inclined lower side for insuring free drainage. The receiver 48 and filter-pan 14 are connected by a detachable nipple 51, threaded at the ends for engaging threaded apertures, respectively, in the filter and receiver. A draw-off faucet 52 is detachably connected to the receiver 48, as by a screw-thread, at 53 and extends 20 through the closure member 41. The draw-off faucet is provided with a transparent stand-pipe 54 exteriorly of the member 41 to denote the stage of water in the receiver, the stand-pipe being closed by a cap 55.
- 25 The receiver 48 will be formed of the same enameled sheet metal employed for other parts of the structure.

30 By this construction it will be obvious that by opening the doors 37 38 and cover 23, lifting out the ice-tray 19, unscrewing the draw-off faucet 52 and nipple 51, removing the closure member 41 by releasing the bolts 46 47, removing the water-receptacle 48, and the partitions 29 30 and shelves 35 36, nothing but the empty casing, and without interior parts, will be left except the supporting-cleats 13 27 28 33 34. Every part of the interior of the casing may thus be readily reached with the cleansing appliances, while 35 at the same time the detached portions, being entirely separable, are also in condition for ready cleansing. This is of the greatest importance in refrigerators, as will be obvious.

40 Hooks 17, on which to suspend articles, are arranged in the provision-chamber, any required number being employed. Ventilator-apertures 49 are also arranged through the walls of the provision-chambers and provided with plugs 50, which may be inserted 45 therein from the outside when required. Thus when warm victuals are placed in the provision-chambers the plugs should be detached until the heat has escaped to prevent the undue influence thereof upon the other 50 articles of food.

45 The device is simple in construction, efficient in action, can be inexpensively manufactured, and adapted to all the various sizes of refrigerators required from the 60 smallest "domestic" to the largest devices

of this class employed by meat and provision dealers.

Having thus described the invention, what is claimed is—

1. In a refrigerator, an inclosing casing 70 having a closure at its upper end and interior supporting-cleats spaced below the closure and an opening in one of its side walls below said cleats, said casing provided with spaced guides upon its floor, a receptacle for filtering material supported upon said cleats and provided with spaced guide members upon its lower face in vertical alignment with the guide members in the floor of said casing, a tray for the ice bearing upon said receptacle and discharging the water resulting from the melting ice into the same, spaced plates extending between said receptacle and the floor of said casing and slidably engaging said guide members, a water-receiver disposed between said plates for receiving the filtered water from said receptacle, a closure for the central portion of said side-wall opening and bearing against said plates, and doors swinging from said casing and closing against said 80 central closure member.

2. In a refrigerator, an inclosing casing having a closure at its upper end and an opening in one of its side walls, a receptacle for filtering material detachably supported within said casing and spaced below said upper end and removable through the same, a tray for the ice bearing upon said receptacle and discharging the water resulting from the melting ice into the same, spaced plates extending between the bottom of said receptacle and the floor of the casing, a water-receiver disposed between said plates for receiving the filtered water from said receptacle, a detachable closure for the central portion of said side-wall opening and bearing against said plates, and doors swinging from said casing and closing against said 90 central closure member.

3. In a refrigerator, an inclosing casing 100 having a closure at its upper end and an opening in one of its side walls, a receptacle for filtering material detachably supported within said casing and spaced below said upper end and with a discharge-pipe depending therefrom, a tray for the ice bearing upon said receptacle and discharging the water resulting from the melting ice into the same, spaced plates extending between the bottom of said receptacle and the floor of the casing, a water-receiver disposed between said plates for receiving the filtered water from said receptacle and coupled to said discharge-pipe, and a detachable closure for the central portion of said side-wall opening and bearing 110 against said plates, and doors swinging from said casing and closing against said central closure member.

4. In a refrigerator, an inclosing casing 115 having a closure at its upper end and with an 120

- opening in one of its side walls, a receptacle for filtering material detachably supported within said casing and spaced below said upper end and with a discharge-pipe depending therefrom, a tray for the ice bearing upon said receptacle and discharging the water from the melting ice into the same, spaced plates extending between the bottom of said receptacle and the floor of the casing, a water-receiver disposed between said plates for receiving the filtered water from said receptacle and coupled to said discharge-pipe, and with a threaded aperture in its outer side, a detachable closure for the central portion of said side-wall opening and bearing against said plates and with an aperture in alignment with said threaded aperture, a draw-off faucet having a threaded terminal for engaging said threaded aperture through the aperture in said central closure member, and doors swinging from said casing and closing against said central closure member at opposite sides of said faucet.
5. In a refrigerator, an inclosing casing having an opening in one of its side walls, a receptacle for filtering material supported within said casing above said opening, a tray for the ice above said filter-receptacle and discharging the water resulting from the melted ice into the filtering material, spaced plates extending between the bottom of said receptacle and the floor of the casing, a water-receiver disposed between said plates for receiving the filtered water from said receptacle, a detachable closure for the central portion of said side-wall opening, and doors swinging from said casing and closing against said central closure member.
10. In testimony that I claim the foregoing as my own I have hereto affixed my signature in the presence of two witnesses.
